UNITED STATES PATENT OFFICE.

MYRON W. BROOKS, OF HERKIMER, NEW YORK, ASSIGNOR OF ONE-HALF
TO HENRY M. QUACKENBUSH, OF HERKIMER, NEW YORK.

GARMENT.

No. 805,052.

Specification of Letters Patent.

Patented Nov. 21, 1905.

Application filed February 28, 1905. Serial No. 246,882.

To all whom it may concern:

Be it known that I, MYRON W. BROOKS, a citizen of the United States, residing at Herkimer, in the county of Herkimer and State of New York, have invented certain new and useful Improvements in Garments, of which the following is a specification, reference being had therein to the accompanying drawings.

10 My invention relates to an improved garment; and I declare that the following is a full, clear, concise, and exact description thereof sufficient to enable one skilled in the art to make and use the same, reference being had 15 to the accompanying drawings, in which like letters refer to like parts throughout.

The invention has to do with a garment to be used as a protector for the head, face, neck, and chest or such of said parts as may 20 be desired, and comprises an article which may be easily folded, extended, and adjusted without the use of any buttons or fastenings to furnish such protection.

In the drawings I indicate different forms 25 of stitches, the parallel lines indicating, for instance, tuck-stitches. Where other lines cross these at substantially right angles I indicate plain stitching or stitches of closer mesh, and where such parallel lines are obliquely crossed by other lines I indicate a 30 stitch of more open mesh—as, for instance, a pineapple-stitch. These stitches can be formed in the knitting of the article by machines which are in common use. The purpose 35 of forming these different stitches is to provide in the garment a portion which is less easily stretched than the parts where tuck-stitches, for instance, are used and at the parts of the garment which lie over the face 40 to permit easy breathing.

In the drawings, Figure 1 is a side view of a figure wearing one of these devices which is in the form of a chest, neck, and head covering, Fig. 2 being a front view of the same, 45 the upper edge, however, coming only to the lower edge of the hat or cap. Fig. 3 is a front view of the article in the form of a muffler adaptable for the protection of the chest, neck, and head. Fig. 4 is a side view showing 50 the protector or garment rolled part way up, and Fig. 5 is a front view showing the protector applied only to the neck and chest portions.

Referring to the figures more in detail, A represents the body of the garment or protector, which I assume in this instance is 55 knitted with tuck-stitches, having at its upper end some rows of plain stitching *a*, which are brought up under the vizor of the cap and over the edge of the cap back of the 60 vizor. In the front portion, as indicated by *b*, where the oblique lines are shown, the garment is knitted with more open mesh, so that the wearer can breathe freely, but still be protected against the weather. The 65 front of the garment has a slot *d*, which is cut across and hemmed or otherwise suitably finished around the edge to form an opening for the eyes. This opening, as well as the edges, may be hemmed or folded over suitably, and, as indicated in *a'* in Fig. 3, an elastic 70 may be inserted in the hem at the top of the garment, so that it will at all times fit snugly to the wearer where adjusted. It will be seen, Fig. 3, that the garment extends 75 downwardly at its front portion a greater or less distance to furnish protection between and below the lapels of the coat. In Fig. 4 it is seen that the upper edge of the garment may be brought up at the back 80 above the rim of the cap or even farther, if desired, the front portion being folded beneath the chin. As indicated in Fig. 2, the upper edge of the protector may be brought only to the edge of the hat or cap, so that the article 85 can be worn with a head-gear of any kind.

The device can be readily put on and taken off without the necessity of removing the gloves or without any of the inconveniences of buttons or other fastenings which are likely 90 to break away or to prove insufficient and add to the clumsiness and detract from the comfort and efficiency of the garment.

My device, as I have indicated, is particularly useful because it can be so easily put on 95 or off and can be adjusted to the needs of the wearer, it being for these and other reasons especially adapted to the uses of automobileists, woodsmen, and others and all who desire an additional protection for occasional 100 use easily removed and applied.

It is of course apparent that instead of knitting this article integral it can be cut out of a blank or made up, being sewed in the proper way to assemble the parts or connect 105 the edges.

Having described my invention, what I claim as new, and desire to secure by Letters Patent, is—

- 5 1. A knitted-fabric garment for the head, open at the top and bottom and elastic around the top opening to hold the garment at various adjustments on the head, and whereby the garment can be rolled around the neck and drawn up at the back of the head.
- 10 2. A fabric head-covering open at the top and bottom and elastic at the top portion to hold the covering at various adjustments on the head, and whereby the covering can be rolled around the neck and drawn up at the 15 back of the head, said covering having a front depending flap to form a chest-protector, substantially as described.
- 20 3. A head-covering open at the top and bottom and hemmed around the top opening, whereby the garment can be adjusted vertically to various positions on the head or around the neck, said garment having a front opening for the eyes and a loosely-hanging

front portion, substantially as and for the purposes described.

4. A knitted-fabric head-covering open at the top and bottom and provided with elastic means around the top opening to hold the covering in various adjustments on the head or around the neck, said covering having an eye-opening and the depending loose-front portion, substantially as described.

5. A knitted-fabric head-covering open at the top and bottom and elastic at the top opening to hold the covering at various adjustments on the head, and whereby the covering can be rolled around the neck and drawn up at the back of the head, said covering having an eye-opening, substantially as described and shown.

In testimony whereof I affix my signature in presence of two witnesses.

MYRON W. BROOKS.
